(57)

CLAIM

The ornamental design for a display shelf, as shown and described.

DESCRIPTION

FIG. 1 is a perspective view of a display shelf;

FIG. 2 is a front view thereof;

FIG. 3 is a left side view thereof;

FIG. 4 is a right side view thereof; and,

FIG. 5 is a top view thereof.

The broken lines shown in the drawings are included for purposes of illustrating portions of the display shelf and form no part of the claimed design.

1 Claim, 5 Drawing Sheets(56)
